DESIGN FOR A TOP FOR A FIELD COOKING STOVE

Styles T. Howard, Jeffersonville, Ind.

Application June 18, 1941, Serial No. 101,533

Term of patent 3½ years

To all whom it may concern:

Be it known that I, Styles T. Howard, a citizen of the United States, residing at Jeffersonville, Indiana, have invented a new, original, and ornamental Design for a Top for a Field Cooking Stove, of which the following is a specification, reference being had to the accompanying drawing, forming a part thereof.

Fig. 1 is a perspective view of a top for a field cooking stove, showing my new design.

Fig. 2 is a similar view thereof with the grate flanges in raised position and with the left panel folded beneath the device; and

Fig. 3 is a side elevational view of the article in Fig. 1 with the flanges and panel in raised position.

I claim:

The ornamental design for a top for a field cooking stove, substantially as shown.

STYLES T. HOWARD,
